UNITED STATES PATENT OFFICE

ALFRED COPONY, OF MOUNT CLEMENS, MICHIGAN, ASSIGNOR TO COPONY AUTO LOADING COMPANY, OF DETROIT, MICHIGAN, A CORPORATION OF MICHIGAN

DECKING DEVICE

Application filed July 2, 1928. Serial No. 289,910.

This invention relates to decking devices and has particular reference to vehicle decking devices for freight cars and the like.

5 The herein described invention relates particularly to apparatus and means for half decking the vehicles as distinguished from double decking and has as one of its primary objects to simplify, render more efficient and 10 improve generally devices of this character.

The several objects, advantages and novel details of construction of this invention will be made more apparent as this description proceeds, especially when considered in 15 connection with the accompanying drawings wherein:

Figure 1 is a fragmentary perspective view of a freight car showing my improved decking device associated therewith.

20 Figure 2 is a fragmentary vertical longitudinal sectional view through a conventional form of freight car showing several vehicles loaded therein.

Figure 3 is a vertical sectional view taken 25 substantially on the plane indicated by line 3—3 in Figure 2, and

Figure 4 is an enlarged vertical sectional view through one of the supporting elements.

Referring now to the drawings wherein 30 like reference characters indicate like parts throughout the several views it will be noted that there is fragmentarily illustrated a conventional form of freight car including a bottom or flooring 10, side posts 11, door posts 12, side plates 13, lower sheathing 14 and end sheathing 15.

Extending longitudinally of the freight car arranged one at each side thereof, are 40 footing strips 16. These footing strips extend between and are supported by the side posts 11 and door posts 12 as will be obvious. The under side of each footing strip 16 is provided with a plurality of recesses or notches 17. Cooperating with these footing

45 strips are supporting beams or members 18 each provided with a notch or recess 19 formed adjacent one end thereof and adapted to engage in any one of the cut-away portions 17 of the footing strip. In practice these supporting beams 18 will general-

ly be furnished by the manufacturer of the vehicles being shipped and each of these beams is provided on the end opposite to the notched end with a boxing strap loop 20 adapted for engagement with the hub of the 55 vehicle to be supported. Obviously these loops may be of any desired length so as to support the end of the vehicle at the proper height from the floor 10.

This present invention constitutes an improved modification of the vehicle decking device shown and described in my copending application Serial No. 277,704. In that application special hangers are employed for bracing or supporting the beams but in the present construction I have substituted other means for supporting these vehicle supporting beams. In the present form of construction I provide a flexible element such as a chain or the like 21 extending longitudinally of the freight car and supported at longitudinally spaced points by means of links or eyelets or the like 22. These supporting eyelets may be carried for instance by the posts 11. One end of the 70 flexible element 21 is permanently secured to door post 12 as for instance by means of a hook or other permanent fastening element 23. The chain or flexible element 21 passes freely through the eyelets 22 so that it can 75 be adjusted longitudinally and looped, for a purpose to be more fully hereinafter referred to, at the points between the posts 11. Carried by one of the posts at the end of the freight car is means for engaging the free 80 end of the flexible element. 85

This means may conveniently be in the form of a hook 24 provided with a safety catch. Arranged at spaced points adjacent the free ends of the flexible element are additional links or loops 25 any one of which is engageable with the hook 24 for lengthening or shortening the effective length of the flexible element 21.

In practice the flexible element 21 is 90 adjusted as regards length as suggested in Figure 1 of the drawings and a supporting beam 18 is engaged with a looped portion 27 of the flexible element in the manner clearly suggested in this figure of the 100

drawings. It will be noted that the supporting beam 18 is provided with an abutment or shoulder 26 and the flexible element is engaged behind this abutment. The 5 notched end of the supporting beam is then fitted into an adjacent notch 17 of the footing strip 16 and the boxing strap loop at the other end of the beam 18 is fitted over the hub of the front wheel of the vehicle 10 being decked. In this manner the flexible element 21 acts to brace or support the beams 18 and when not in use may be conveniently disposed out of the way in the space behind the footing strip 16.

15 This flexible element 21 also forms an entirely satisfactory and convenient means for supporting the beams 18 as it may be readily adjusted and may be manipulated with facility.

20 Obvious modifications will suggest themselves to those skilled in this art and to this end reservation is made to make such changes in many of the essential and all of the non-essential details of construction as 25 may come within the purview of the accompanying claims.

What I claim as my invention is:

1. In a decking device for freight cars, a 30 footing strip extending longitudinally of the car, a vehicle supporting beam engageable with said footing strip, and a flexible element extending longitudinally of the car and adapted for engagement with said beam for bracing the same to allow selected positioning of the vehicle.

2. The combination with a freight car, of a vehicle decking device including a longitudinally extending footing strip, a beam having one end engageable with said footing strip and a longitudinally extending flexible element adapted for engagement with said beam at a point spaced from said 40 footing strip for bracing said beam.

3. In a vehicle decking device for freight 45 cars, a footing strip extending longitudinally of the car, a vehicle supporting beam having one end engageable with said strip and a flexible element slidably engaging supports spaced longitudinally of the car and 50 adjustable as to length whereby said flexible element may be looped under said beam adjacent its outer end thereof to support the same.

4. The combination with a freight car of a 55 vehicle decking device including a supporting beam, beams extending longitudinally of the freight car for supporting one end of said beam and a flexible element slidably supported longitudinally of said freight car 60 at spaced points throughout its length and capable of being looped intermediate its supports for engagement with said supporting beam adjacent the free end of the latter, for the purpose set forth.

15 5. The combination with a freight car,

of a vehicle decking device including a footing strip extending longitudinally of the car, a supporting beam having one end adapted for engagement with said footing strip, a flexible element having one end permanently secured to a portion of said car, supports spaced longitudinally of said car with which said flexible element slidably engages, and means for adjustably securing one end of said flexible element whereby 70 said flexible element may be looped at points intermediate the supports therefor for engagement with said beam at a point spaced from said footing strip, for the purpose set forth.

6. In a decking device for freight cars, a vehicle supporting beam extending transversely of the car and having one end adjustably engaging a member carried by a side wall of the car, for movement longitudinally of the car, and a flexible element extending longitudinally of the car and adapted for engagement with said beam adjacent the outer end thereof for bracing the beam in any adjusted position of the 90 latter.

7. In a decking device for freight cars, a longitudinally adjustable vehicle supporting beam extending transversely of the car and having one end detachably engaging a member carried by a side wall of the car, and an adjustable flexible element extending longitudinally of the car and adapted for engagement with said beam adjacent the outer end thereof for bracing the beam in 100 any of the adjusted positions of the latter.

8. In a vehicle decking device for freight cars, a supporting beam adapted for adjustment longitudinally of the car, and a flexible element extending longitudinally of the car and movable to engage and brace said beam in its various positions of adjustment.

In testimony whereof I affix my signature.
ALFRED COPONY.
